UNITED STATES PATENT OFFICE.

CLINTON H. M. BULL, OF HOUSTON, TEXAS, ASSIGNOR TO REED ROLLER BIT COMPANY, OF HOUSTON, TEXAS, A CORPORATION OF TEXAS.

ROLLER CUTTER.

Application filed March 28, 1927. Serial No. 178,987.

This invention relates to roller bits for use in deep well drilling, and more particularly to roller cutters adapted to be mounted in said bits.

5 The object of the invention is to provide a roller cutter having a removable point section which can be replaced when worn.

A further object of the invention is to provide a roller cutter with teeth thereon 10 having an efficient cutting operation.

Another object of the invention is to provide a new and improved mounting for roller cutters.

15 Various other objects will be apparent from the following description:

The preferred embodiment of the invention is illustrated in the accompanying drawings, in which Fig. 1 is a side elevation of the cutter, and Fig. 2 a sectional view 20 thereof.

Referring specifically to the drawings, the bit head is indicated at 1, and has a recess 2 in the outer face thereof and a bore 3 leading inwardly from said recess and 25 adapted to receive spindle 4, spindle 4 being secured in the head by nut 4^a. Head 1 is also provided with an annular flange 5 projecting inwardly adjacent the inner end of bore 3.

30 The base section 6 of the cutter is mounted on the head, and has a central opening 6^a to receive annular flange 5, a bushing 7 being interposed therebetween. Base section 6 is provided with a recess 6^b to receive the 35 enlarged portion 4^b of spindle 4 and the annular flange 8^a of point section 8.

Annular flange 8^a forms a recess in point section 8 to receive the end of spindle 4, and has a plurality of screw-threaded bores 40 8^b, to receive screw-threaded pins 9, said pins being adjustable inwardly into groove 4^c in spindle 4, to rotatably lock the point section on spindle 4 and in the recess 6^b of base section 6. Annular flange 8^a of point 45 section 8 fits snugly in recess 6^b of base section 6 so that it is firmly supported laterally by the walls of recess 6^b and longitudinally by the enlarged portion 4^b of spindle 4, but at the same time is free to revolve. The 50 engagement of pins 9 in groove 4^c serves merely to prevent point section 8 from slipping out of base section 6 when the bit is not in use or when it is being lowered in or removed from the hole. When the bit is 55 operating upon the bottom of the hole, the

pressure against it serves to hold the point section in place.

Spindle 4 has a key 4^d. Bushing 7 and annular flange 5 have slots 7^a and 5^a, respectively, into which key 4^d enters to prevent rotation of spindle 4 and bushing 7.

Teeth 8^e of point section 8, as shown, are formed out of alignment with the teeth on base section 6, and larger than would be the teeth on the corresponding point portion 60 of a single piece cutter with teeth converging from base to apex. Point section 8, immediately at the apex thereof, has four teeth 8^d. The number and arrangement of these teeth may, of course, be varied. The specific 65 form shown, however, being the preferred 70 embodiment.

The assembly and features of the elements 75 constituting the invention, may be outlined as follows:

Bushing 7 is first placed upon annular flange 5. Base section 6 is then slipped upon 80 said washer.

The end of spindle 4 is inserted in the recess in point section 8 formed by flange 8^a, and pins 9 are screwed inwardly so that the inner ends thereof enter groove 4^c in spindle 4. Bores 8^b and pins 9 have cooperating reduced portions, as shown, whereby the inward movement of pins 9 is so limited 85 as to prevent frictional contact thereof with the bottom of groove 4^c. The ends of flanges 8^a are now immediately adjacent but not in frictional contact with enlarged portions 4^b of spindle 4.

90 Spindle 4 with point section 8 mounted thereon is then slipped outwardly through base section 6 and bore 3 of head 1, and nut 4 is screwed onto the screw-threaded end thereof to lock it in the head.

95 When spindle 4 was thus inserted, key 4^d thereof entered slots 5^a and 7^a of flange 5 and bushing 7, respectively to lock spindle 4 and washer 7 against rotation. When 100 spindle 4 was drawn by nut 4^a, enlarged portion 4^b was brought tightly against flange 5 and bushing 7, and loosely in contact with base section 6 to rotatably hold the same in position. Flange 8^a of point section 8 entered recess 6^b in base section 6 to gain a 105 strong lateral support, and be rotatable therein.

110 It is well known in the art that in the use of conical roller cutters, the points thereof are subjected to a great deal of wear-

ing action and the teeth of such cutters become so badly worn near the point of the cutter, where they are smaller than at the base, as to seriously impair the operation of the bit, that portion of the teeth near the base remaining comparatively sharp. Cutters thus worn must be thrown away. The invention provides removable point sections which can be replaced when worn, the old base sections being used with the new point sections. And that the point sections may wear less rapidly and perform more efficiently, the invention provides teeth thereon of comparatively greater size. The placing of these teeth out of alignment with the teeth on the base section produces a more effective disintegration of the material encountered, and also serves to prevent material in the valleys of the teeth moving outwardly from entering the valleys of the teeth on the base section.

It will be noted further that base section 6 and point section 8 are rotatable independently of each other, and will therefore 25 rotate according to the respective pressures upon them.

The invention as defined in the following claims is not limited to the specific construction illustrated and described.

30 I claim:

1. In a rotary boring drill, a spindle having an enlarged portion and a roller cutter having a base section and a point section, said base section resting against the inner face of said enlarged portion, and said point section resting against the outer face of said enlarged portion and being rotatably secured to said spindle.
2. In a rotary boring drill, a spindle having an enlarged portion and a roller cutter having a base section and a point section, said base section having a recess against the bottom of which said enlarged portion rests, and said point section resting on the enlarged portion and having a recess in which the end of the spindle is rotatably secured.
3. In a rotary boring drill, a head having an annular and slotted flange projecting therefrom, a spindle removably secured in said head and having a key fitting in the slot of said flange and an enlarged portion resting on said flange, a roller cutter hav-

ing a base section and a point section, said base section being rotatable on said flange and resting against said enlarged portion, 55 and said point section being mounted on said spindle and resting against said enlarged portion.

4. In a rotary boring drill, a head having a bore and an annular flange, a roller cutter having a base section and a point section, said base section having an opening to receive said flange, and a recess, said recess being of such depth that the end of the annular flange projects above the plane of 65 the bottom of said recess, and a spindle fitting in said bore and having an enlarged portion to bear against said flange, said point section fitting within said recess and resting against said enlarged portion. 70

5. In a rotary boring drill, a head having a bore and an annular slotted flange, a roller cutter having a base section and a point section, said base section having an opening to receive said flange, and a recess, a spindle 75 fitting in said bore and having a key resting in the slot of said flange, said point section being rotatably and removably secured in said recess.

6. In a rotary boring drill, a head having 80 a bore and an annular slotted flange, a slotted bushing surrounding said flange, a roller cutter having a base section and a point section, said base section having an opening to receive said flange and bushing, and a recess, 85 a spindle fitting in said bore and having a key resting in the slots of said flange and bushing, said point section being rotatably and removably secured in said recess.

7. In a rotary boring drill, a head having 90 a bore and an annular flange adjacent said bore, said annular flange being diametrically slotted, a spindle resting in said bore and having a transverse key fitting in the slot of 95 said flange, and a roller cutter mounted on said spindle.

8. In a rotary boring drill, a head having an annular flange thereon, a bushing on said flange, said flange and bushing being slotted, a cutter, and a spindle on which said cutter is mounted, said spindle having a key fitting in the slots of said flange and said bushing. 100
